UNITED STATES PATENT OFFICE.

WILLIAM SEBASTIAN GRAFF BAKER, OF BALTIMORE, MARYLAND.

CAR-TRUCK.

SPECIFICATION forming part of Letters Patent No. 426,096, dated April 22, 1890.

Application filed February 20, 1890. Serial No. 341,163. (No model.)

To all whom it may concern:

Be it known that I, WILLIAM SEBASTIAN GRAFF BAKER, a citizen of the United States, residing at Baltimore city, in the State of Maryland, have invented certain new and useful Improvements in Car-Trucks, of which the following is a specification.

My invention relates more especially to the organization of electric car-trucks.

10 In Letters Patent No. 415,892, granted to me November 26, 1889, I have shown a car-truck in which the wheel-brakes are each mounted independently on the side beams of the depending frame of the truck, which is supported from the axle-boxes by brackets or down-hangers resting thereon. The brakes are joined by link-connections to the rock-shaft extending across the truck and provided with an operating-lever. In my present invention this general organization is adhered to, but the rock-shaft is connected to the wheel-brakes by adjustable rods provided at their inner ends with curved toothed heads or racks engaging with toothed wheels or pinions on the rock-shaft.

25 The details of construction and the subject-matter claimed are hereinafter designated.

In the accompanying drawings, Figure 1 is a side elevation of a car-truck embodying my invention. Fig. 2 is a transverse section on the line 2 2 of Fig. 1. Fig. 3 is a detail view, partly in side elevation and partly in section, of the brake mechanism. Fig. 4 is a detail plan view of the inner ends of the rods which connect the wheel-brakes to the rock-shaft. Fig. 5 is a detail view in section on the line 5 5 of Fig. 4.

The depending frame of the truck may be constructed with side beams A and life-guards B and suspended from the axle-boxes C by brackets or down-hangers D. The axle-boxes C are free to move vertically in pedestals E, the lower ends of which are connected by cross-bolts F and frame-bars G, and braces H 40 connect with the pedestals and hold them rigidly in place.

The car-frame is supported on springs I, as in my patent above mentioned.

The wheel-brakes J are independently 50 mounted on the side beams A by vertical pivoted links K. The lower ends of these links

are pivoted to the side beams by bolts K' and their upper ends are pivoted to blocks L on cross-bolts L'. The end of each block L next to the wheel is provided with a dovetailed tongue l, which fits in a corresponding recess l' in the outer face of the brake-shoe.

A bolt l² extends vertically through the backwardly-extending arms l³ of the shoe and through the dovetailed block L. The end of the bolt projecting through the lower end of the brake-shoe is provided with a suitable key or lynchpin l⁴. By this construction, it will be observed, the brake-shoe may be easily removed by withdrawing the bolt l² and sliding the shoe laterally relatively to the block L. The blocks L are formed with inwardly-projecting arms M, which are screw-threaded internally and receive the screw-threaded ends of the connecting-rods N. The opposite ends of the rods enter the internally-screw-threaded shanks O' of the toothed rods or racks O. These racks are each formed with a curved toothed portion o and with an annular guide-piece o'. The guide-piece o' of each toothed head embraces the shank of the opposite rack-bar and on each side of the car one rack-bar is arranged over the rock-shaft and the other beneath it.

The rock-shaft P is mounted in suitable 80 bearings in brackets or standards Q, secured to the side beams A, to which are also secured the channeled arch-beams R, which extend across the truck and support the devices S, to which the electric motors are secured. 85 At each end of the rock-shaft is secured a pinion or toothed wheel p, provided with teeth p' on opposite sides adapted to engage with the teeth in the rack-bars O. An operating-lever T, secured to the rock-shaft, may also 90 be provided with an operating-rod T', extending to the end of the truck to be operated in the usual way. The brakes are normally held out of engagement with the wheels by a weighted counterbalancing-arm U, secured to 95 the rock-shaft, preferably immediately below the operating-lever; or a spring may be provided for the same purpose.

In the drawings the brakes are shown as withdrawn from the wheels. By turning the 100 lever T to the right the rock-shaft is revolved and pushes the rack-bars, connecting-rods,

and brakes in opposite directions to apply the brakes to the wheels. The construction shown is strong and powerful.

The brakes may be readily adjusted by the rods N, which are provided with opposite screw-threads on their opposite ends to compensate for wear, each brake being independently adjustable, as it is independently mounted on the depending frame of the truck 10 and independently connected with the rock-shaft.

The brake-operating mechanism is mainly confined to the sides of the car, the only cross-connection being the rock-shaft, which 15 does not interfere materially with the electric-motor mechanism.

I claim as my invention—

1. The combination, substantially as hereinbefore set forth, of the car-truck, the depending frame, the wheel-brakes, each mounted independently on the depending frame, the rock-shaft having pinions or toothed wheels thereon, the toothed heads or rack-bars engaging therewith, and the rods connecting them with the wheel-brakes. 25

2. The combination, substantially as hereinbefore set forth, of the car-truck, the wheel-brakes, the rock-shaft extending across the truck and having pinions or toothed wheels 30 on its opposite ends, the toothed heads or rack-bars engaging with the pinions on the rock-shaft, and the horizontal connecting-rods extending through guides on the rack-bars and connecting the rack-bars with the wheel- 35 brakes.

3. The combination, substantially as hereinbefore set forth, of the car-truck, the axle-

boxes, the side beams of the depending frame, the brackets or down-hangers resting on the axle-boxes and supporting the side beams, 40 the brake-shoes, the dovetailed blocks fitting in the brake-shoes, the vertical bolts securing the blocks to the shoes, the links connecting them to the side beams of the frame, and means for operating the brakes. 45

4. The combination, substantially as hereinbefore set forth, of the car-truck, the depending frame, the brackets secured to the frame and resting on the axle-boxes, the arched connecting-bars extending across the 50 truck, the transverse rock-shaft, the wheel-brakes, and connections between the wheel-brakes and the rock-shaft.

5. The combination, substantially as hereinbefore set forth, of the axle-boxes, the side 55 beams, the brackets resting on the axle-boxes and supporting the side beams, the brake-shoes, each mounted independently on the side beams, the rock-shaft, the weighted lever thereon, and connections between the rock-shaft and the wheel-brakes for operating them. 60

6. The combination, substantially as hereinbefore set forth, of the wheel-brakes, the rock-shaft, the rack-bars engaging with pinions on the rock-shaft, and the connecting-rods provided with opposite screw-threads on their opposite ends and connecting the rack-bars with the shoes. 65

In testimony whereof I have hereunto subscribed my name.

WILLIAM SEBASTIAN GRAFF BAKER.
